INVERTED PISTON PUMP

Christian Rokkjar, Sedro Woolley, Wash.

Application June 23, 1937, Serial No. 149,967

3 Claims. (Cl. 103—182)

My present invention relates to fluid pumps and more particularly to an inverted piston pump.

There are many types of pump constructions, especially for pumping water, available on the market. These, however, are characterized by either providing pumps that are constructed to operate reciprocating pistons, that operate on the centrifugal principle, or pumps that may be generally classed as gear, or rotor, pumps. Each of these requires careful machining and unless they are of the more expensive type using multiple units they cannot be depended upon to supply a uniform flow of liquid. The controlling factor that makes these pumps expensive in manufacture is the requirement of accurate machine work and the fact that they are normally intended to work against considerable head. In my present invention, however, I am endeavoring to supply the demand for pumps that will work against only a nominal head and, as a result, I am able to provide a pump having a short stroke and a moderately large bore. This form of construction lends itself to economical manufacture. It is no longer necessary to have a crank to reciprocate the piston. The valving arrangement can be greatly simplified and the short stroke permits the use of eccentrics for reciprocating the pistons which in my present design are arranged to rock in the cylinders, due to their slight angular displacement, instead of being connected to a crank shaft by the conventional connecting rod or cross head assembly which is required when the piston reciprocates in the normal manner.

I further provide in my present design a very simple construction wherein the piston assembly, or assemblies, in a multi-cylinder unit is disposed in the lower part of my pump chamber and as the water is drawn through the piston into the chamber it has at all times a volume of air that is compressed above the water so as to provide an air dome that will equalize the pressure and maintain a substantially even flow on the outlet or discharge line.

Other and more specific objects will be apparent from the following description taken in connection with the accompanying drawings, wherein—

Figure 1 is a longitudinal vertical section through a pump made after the teachings of my present invention.

Figure 2 is a cross-sectional view through one cylinder of the pump shown in Figure 1, the cutting plane being taken at right angles to that figure.

Figure 3 is a side elevation of my pump showing the same as connected to an electric motor.

Figure 4 is a cross-sectional view taken along the line 4—4 of Figure 1.

Figure 5 is a cross-sectional view taken along the line 5—5 of Figure 1.

Figure 6 is a cross-sectional view taken along the line 6—6 of Figure 1.

Figure 7 is a cross-sectional view taken along the line 7—7 of Figure 1.

Referring to the drawings, throughout which like reference characters indicate like parts, 8 designates the upper pump chamber which is adapted to be fixedly secured as by bolts 10 to the base housing 12. Secured between housing members 8 and 12 is the cylinder unit 14. This unit is entirely separate from members 8 and 12 and may be supplied to accommodate any reasonably desirable number of pistons. Through- 10 out the present drawings I have shown a three-cylinder unit. It is believed it will be apparent that if only the capacity of a one-cylinder pump is needed, only one such piston assembly would be employed. If it is necessary to increase the ca- 20 pacity two or more cylinders might be used or if desirable the entire housing 8 and 12 might be lengthened to provide any reasonable number of cylinders.

Each cylinder as 16 is provided with relatively short walls and has disposed in the lower portion a plate or disc valve 18. This valve is urged, by spring 20, to cover a plurality of openings as 22 and thus provide the intake valve for my pump cylinder. Disposed within cylinder 16 is piston proper 24. This member is provided with a relatively short skirt which is used to seat a flexible cup washer 26. This cup may be made of any suitable material, which should necessarily be selected in accordance with the fluid to be pumped; for water a leather or composition cup is probably most desirable.

To further assure an even flow of water into the intake valve chamber I provide that the intake valve itself be placed at the extreme bottom of the cylinder member 16 and, as no provision is made to fully exhaust the air from the chamber below baffle 14, a certain amount of air will be trapped there which will function as an air dome. This, under certain conditions of use, is very desirable and with a single cylinder unit it is necessary that a greater air volume be provided. This in my present arrangement is automatically assured in that, if only one cylinder is used, there will be a large volume below baffle 14; and, as each additional cylinder is installed, there will be a corresponding reduction in the volume of this lower chamber.

Fixedly secured to piston 24 is piston rod 28. This rod is probably best illustrated in Figures 1 and 2. It is balled out at its lower end so as to provide one of the seat members for the cup 26, it being preferably threaded, or otherwise secured, to the lower piston member 24. This piston member is provided with a valve quite similar

to valve 18 in that it has a plate or disc 29, of suitable material, which is adapted to cover openings 30, in member 24, and is urged into its closed position by spring 32.

5 The upper end of piston rod 28 is provided with a circular bearing portion 34 in which is disposed a suitable, preferably, fibrous bushing 36. It must be remembered that this assembly will be working in liquid and in the case of water it 10 is very desirable that some form of bearing that has been found satisfactory for use in water should be used. In general those types of bearings that are used in the stern bearing of boats and the like will prove satisfactory. These at 15 present are being made of composition material some being largely asbestos, lignum-vitae and babbitt are often used and in some of the later installations the fluted rubber bearing is used.

Operatively engaging bushing 36 is eccentric 38. 20 This member should be preferably of a rustproof or stainless material such as Monel metal or stainless steel, or some of the various bronze bearing alloys. The eccentrics are secured as against rotation on shaft 40 by any suitable 25 means. As at present constructed I prefer to use a Woodruff type of key 41, in the left hand eccentric as viewed in Figures 1 and 7, and to suitably secure the other eccentric to this one by some convenient means. In Figure 2 and particularly in Figure 7 I have shown this as accomplished by using dowel pins as 41a. It will be apparent it is believed that other suitable keying 30 means might be provided or the abutting faces of the different eccentrics might be deformed so 35 that the members would engage in locked relationship.

Inasmuch as the pump is designed to operate 40 against low pressures there is no objection to having a relatively large area to piston 24, consequently, the stroke can be reduced to a point where eccentric operation is satisfactory. Shaft 40 is provided with a journal at one end in bushing 42 and at its other end, which must take the belt tension, it is provided with preferably an 45 antifriction bearing capable of carrying in addition to the radial loading a certain amount of thrust loading. The roller type of bearing shown at 44 has been found to be very satisfactory. This bearing is best supported, as indicated, in 50 a separate collar 46 which while normally formed in the same casting with housing 8, is spaced therefrom as by the spider arrangement 48 so that packing can be renewed and adjusted and any leakage that might pass through packing 58 55 and packing gland 51 will be dissipated down the side of housing 8 and will not enter the bearing housing which must of necessity be protected as by lubricant retainers 53 and 54. A further advantage of this construction is that packing gland 60 nut 51 is readily reached for adjustment or for the replacement of packing 58. It is desirable, if a roller bearing is used as is indicated in Figure 1, that the bearing be so placed as to take 65 thrust from the pump cavity as it will be apparent that the pressure built up within the pump will be applied to the end bushing 56, secured to shaft 40; when the bearing is so placed it will be properly seated by the pump pressure which further tends to seat the various units in a fixed 70 relationship with one another.

In order to effect an easily assembled unit I provide first that shaft 40 be threaded or otherwise secured within a bearing member 56, the outside diameter of which is the body size of the 75 spacer bushing on shaft 40. Bearing 56 is in

turn journaled within bushing 42. It has been found most convenient to assemble the eccentrics used on a short shaft not longer than the total length of the eccentrics used, these are then put in place and shaft 40 is passed through discharge opening 64 with key 41 and sleeve 56 in place and it is then threaded through the different eccentrics and at the same time it expels the short shaft which will pass out through the opening provided for packing 50. It will be seen from 10 Figure 1 that the height of key 41 does not exceed the height of the spacers or bushings 58 that are disposed upon shaft 40. When the eccentrics are in place each surrounded of course by its piston rod 28, bushing 58 is installed, then bearing 44 15 and finally after the lubricant retaining rings 53 and 54 are screwed in place, fly wheel 60 is placed on the shaft and secured thereon as by nut 62. Tightening this nut forces all the bushings and eccentrics against bearing 44. 20

As an aid in assembling the unit I provide that the discharge opening will be at 64 co-axially with shaft 40 and of a sufficient size so that the shaft bushings can pass therethrough. The intake of the pump is provided at 66 where the 25 fluid entering the pump then passes up through the screen 68. It will be understood, it is believed, that any suitable source of motive power might be employed. In Figure 3 I have shown the electric motor 70 connected as by belt 72 30 to the pulley or fly wheel shown at 60.

The foregoing description and the accompanying drawings are believed to clearly disclose a preferred embodiment of my invention but it will be understood that this disclosure is merely illustrative and that such changes in the invention 35 may be made as are fairly within the scope and spirit of the following claims.

Having thus fully described my invention, what I claim as new and desire to secure by Letters 40 Patent is:

1. In a liquid pump, the combination with an upper casing, a base, an intermediate partition having an integral annular series of open-top ported cylinders projecting on diagonal lines, 45 exterior tie bolts connecting said base and casing and spring-pressed valves in said cylinders, of a rotary shaft journaled in the casing and a series of stems eccentrically mounted thereon, said stems each having a hollow head and a ported 50 piston mounted in said head a spring-closed valve for each piston, and said pistons being oscillatable and reciprocable in the cylinders.

2. In a liquid pump the combination with a pump casing and its rotary shaft, an end bearing 55 for the shaft in one wall of the casing and outlet ports adjacent said bearing, a packing nut in an opposite wall for said shaft, an exterior spider-frame rigid with the latter wall and a bearing-collar rigid with the frame, a bearing for the 60 shaft within said collar, and closures for said bearing at the opposite ends of the collar.

3. In a liquid pump, the combination with a hollow base having a screened-bottom-intake, an upper casing having a central lateral outlet, an intermediate partition having an annular series of integral diagonally projecting cylinders having intake ports and valves, and exterior tie bolts connecting the base and casing, of a rotary shaft 70 journaled in the casing, a series of stems eccentrically mounted on the shaft, and oscillatable valved-pistons on the stems reciprocable in the cylinders.
